Patented May 12, 1914.

UNITED STATES PATENT OFFICE.

SARA L. W. COE AND HENRIETTA T. WERDEN, OF NEW YORK, N. Y.

COIN-OPERATED DEVICE FOR VENDING-MACHINES.

1,096,353.

Specification of Letters Patent.

Patented May 12, 1914.

Application filed June 20, 1912. Serial No. 704,908.

To all whom it may concern:

Be it known that we, SARA L. W. COE and HENRIETTA T. WERDEN, citizens of the United States, residing at New York, in the county of New York and State of New York, have invented certain new and useful Improvements in Coin-Operated Devices for Vending-Machines; and we do hereby declare the following to be a full, clear, and 10 exact description of the invention, such as will enable others skilled in the art to which it appertains to make and use the same.

This invention relates to improvements in vending machines and more particularly to devices operable by the insertion of coins to control the operation of the vending means,—the object of our present invention being to provide simple and efficient devices in the coin chute to control the passage of 20 coins to the trip of the vending means, said devices being constructed and adapted to permit only a plurality of coins to pass to the trip, whereby the machine will be adapted for vending articles, such as postage 25 stamps, for which more than one cent (two cents for example) is charged.

With this object in view, the invention consists in certain novel features of construction and combinations of parts as hereinafter set forth and pointed out in the 30 claim.

In the accompanying drawings, Figure 1 is an elevation of a stamp vending machine embodying the improvements; Fig. 2 is an 35 elevation of the opposite side of the mechanism; Fig. 3 is a transverse vertical sectional view, and Fig. 4 is a section on the line $\alpha-\alpha$ of Fig. 2.

1 represents a suitable frame, in which a 40 feed drum 2 is mounted and to which a stamp strip is suitably guided from a supply roll,—a shoe 3 being provided for guiding the strip over the drum and causing a stop to be projected through a slot in the frame when the feed drum is turned. A spring-pressed dog 4 is provided for co-operation with pins or projections on the drum for turning the latter, and this dog is 45 pivotally supported by an arm 5 secured to a shaft 6 mounted in the upper portion of the frame. The shaft 6 also carries an arm 7 which normally projects in line with a coin slot 8 in the top of the casing and in line with the upper end of a vertical coin 50 chute 9. When a coin is passed through the slot 8, it will engage the arm 7 and cause the

shaft 6 to be turned and the arm 5 and dog 4 to be moved back against the resistance of a spring 10. The drum is engaged by a suitable trip device connected to a shaft 11 in the lower portion of the frame, and a weighted trip arm 12 projects laterally from the shaft 11 and passes freely across the lower portion of the coin chute 9. When the coins reach the trip arm and depress the same, the feed drum will be released, and the spring 10 will, through the medium of the arm 5 and dog 4, propel said drum and cause the feeding of a stamp through the discharge slot.

The coin chute 9 comprises two vertical plates spaced apart sufficiently to permit the free passages, flatwise, therethrough, of the coins. The chute is made with a laterally-projecting portion at its upper end so as to be disposed under the coin slot 8 while the major portion of said chute is disposed vertically above the trip arm. In order to prevent coins from accidentally lodging in the chute, square corners between vertical and lateral portions of the chute are avoided, and the spacing strip 14, which also constitutes a trackway for the coin, is curved as shown in Fig. 1. The upper end of the chute is notched, as at 15, for the accommodation of the arm 7.

It is desirable to provide a stamp vending machine for two-cent stamps, and to so arrange the coin controlling devices, that the vending mechanism will be released after 90 two cents have been inserted. To accomplish this by simple and efficient means, is the principal object of the present invention.

An arm 16 is pivotally hung on a flange 95 17 at one edge of the chute and normally rests with its vertical edge against the outer vertical portion of the spacing strip 14, in which position, it is normally retained by a weight 18 on said arm. The arm 16 is provided at its lower end with a curved finger 19 which passes freely through the edge-wall of the chute and terminates within the latter. At its free inner end, the finger 19 is provided with a depending toe 20, which, 100 when the arm 16 and its finger 19 are moved outwardly, will rest in a notch 21 in the edge-wall of the chute and aline with the inner face of the latter. The weight 18 will be such that the device will be overbalanced by the weight of two cents and permit the release of the coins. When one cent 110

is inserted through the coin slot, the mechanism will be set as before explained, and the cent will drop upon the free end of the finger 19, but the weight of a single cent 5 will be insufficient to move said finger out of its path. Another cent is then inserted, and will drop upon the cent first inserted. The combined weight of the two cents upon the finger 19, will overbalance the weight 10 18, causing the finger to move back and releasing the two cents, the elongated bearing for the cents, afforded by the toe 20, serving to retain the finger out of the path of the cents through the chute, until both cents 15 shall have passed. When the cents shall have been released, they will drop upon the trip arm and release the winding mechanism.

Having fully described our invention, 20 what we claim as new and desire to secure by Letters-Patent, is:—

In a vending machine, the combination

with an upright coin chute having a hole and a recess in one wall, and a trip device having a part entering the lower portion of 25 said chute, of a weighted member pivotally supported on its upper end exteriorly of the chute, said weighted member having a curved arm passing through the hole in the wall of the chute, said arm having a depending toe at its free end to enter the recess in the wall of the chute and constitute a portion of the wall of the latter, said weighted member constructed to be overbalanced by a plurality of coins on its 30 35 curved arm.

In testimony whereof, we have signed this specification in the presence of two subscribing witnesses.

SARA L. W. COE.

HENRIETTA T. WERDEN.
